UNITED STATES PATENT OFFICE.

MICHAEL W. McARDLE, OF CHICAGO, ILLINOIS.

SPRAY NOZZLE.

Application filed February 6, 1926. Serial No. 86,370.

The purpose of this invention is to provide an improved and simplified construction of a spray nozzle for discharging a stream of water with wide distribution over the area within its range, avoiding the common defect of so-called spray nozzles that the stream is almost wholly diverted from a central area surrounding the position of the nozzle. It consists in the elements and features of construction shown and described as indicated in the claims.

In the drawings:

Figure 1 is a side elevation of a spray nozzle embodying this invention.

Figure 2 is an axial section of the same.

Figure 3 is an axial section of the two body members unscrewed from each other and shown on a large scale, and a valve stem in the form for entering the aperture in a bridge in which it is eventually secured by upsetting or riveting over the end.

Figure 4 is a plan view of a spider which constitutes partial means for limiting the unscrewing of the two body members which might otherwise occur in the adjustment of the nozzle for range of spread.

Figure 5 shows a split ring snap spring which cooperates with the spider for the function stated.

The spray nozzle shown in the drawings comprises two hollow body members, A and B, screwed together, the member, A, being interiorly threaded at the larger end for coupling to a water distributing pipe as a hose pipe, and may be referred to as the rear or base member. The member, B, is exteriorly threaded at the rear end for screwing into the interiorly threaded forward end of the member, A, and at its forward end comprises the widely flared discharge mouth of the device. This member may be referred to as the forward body member. This forward member is constricted as to its cavity intermediate the ends, forming a limited fluid port, 10, and a rearwardly-facing valve seat, 11, back of that port, while forward of the port the cavity is expanded at a wide angle, more than 90° as shown, constituting a flaring discharge mouth for wide distribution of the shower which it is the purpose of the construction to deliver. The rear member, A, has rigidly mounted in a bridge bar, 12, with which said member is provided, the valve having its stem, 15, reduced at the end to form a shoulder, 15^a, fixed longitudinally stopped in both

directions in said bridge bar, by said shoulder and the upset or riveted-over end, 15^b and its head, which is tapered at a wide angle, seating on the seat, 11. The valve 60 has an extension, 13, protruding through the port, 10, and terminating in a slight enlargement, 16, which has the function of assisting in deflecting outwardly the water which derives an oblique angle of discharge 65 in passing between the tapered valve head and the correspondingly tapered seat, causing the stream to take the form of a hollow cone lining the conically flared mouth. At the extremity of this flaring mouth there is 70 formed a slight inwardly projecting lip, 20, which has the purpose and effect of deflecting a limited portion of the wide spread discharge back inwardly for covering the central part of the area within the annular zone 75 covered by the remainder of the stream deflected at the wide angle of the flaring mouth.

It will be understood from the foregoing description that the nozzle is opened by unscrewing the member, B, from the member, A, extending the over-all length of the fixture, and moving the seat of the valve away from the valve; and that the nozzle is closed by screwing the member, A, into the member, B, moving the seat of the valve down onto the valve, diminishing the over-all length of the fixture. In the absence of preventive means it will be seen that there will be liability to entirely unscrew the 90 member, B, from the member, A, in the adjustment for opening the nozzle and adjusting it. This liability is avoided by the provision of a spider, 21, fitted for sliding on the stem of the valve back of the head, 95 and diametered as to its three arms, 21^a, for spanning the cavity of the member, B, back of the constriction in which the port and valve seat are formed; and providing for co-operating with this spider a split ring 100 snap spring, 22, which is snapped into an interior annular groove, α , formed near the inner or lower end of the member, B, the diameter of the wire of which this ring is formed being greater than the depth of 105 the groove, so that the wire projects into the cavity of the member, B, back of the ends of the spider arm, and serves as a check or stop for the spider, preventing it from escaping from the cavity of the member, B, 110 and preventing the member, B, from being withdrawn unless enough force is applied

for unscrewing said member from the member, A, to crowd the snap spring out of the groove.

I claim:

- 5 1. A spray nozzle having its discharge terminal furnished with a widely tapered smooth mouth for spread of the spray and a water inlet thereto substantially axial with respect to said mouth, said mouth being 10 finished at its outer margin with a slightly inturned flange, whereby the outermost portion of the spread stream is deflected inward for covering the central area from which the discharge is diverted by the spreading 15 means of the nozzle including said widely tapered mouth.

2. A hose discharge nozzle comprising two hollow members screwed together, the forward member having an inwardly facing 20 valve seat, a valve carried by the rear mem-

ber and longitudinally stopped therein, and having its head adapted to co-operate with said inwardly facing seat for closing the water passage, and co-operating means on the valve stem and the forward member for 25 stopping the opening movement of the valve; whereby the valve member constitutes means for preventing the unscrewing of the two hollow members from each other, said co-operating means comprising a spider slid- 30 ily fitted on the valve stem and rigidly dimensioned for spanning the axial cavity of the nozzle, the latter having toward the inner end of the forward member an internal groove, and a split ring spring sprung 35 into the groove behind the spider.

In testimony whereof, I have hereunto set my hand at Chicago, Illinois, this 3rd day of February, 1926.

MICHAEL W. McARDLE.
